UNITED STATES PATENT OFFICE.

ERNEST G. MCLEOD, OF BROCKTON, MASSACHUSETTS.

FOUNTAIN-PEN.

1,093,712.

Specification of Letters Patent. Patented Apr. 21, 1914.

Application filed August 2, 1912. Serial No. 712,915.

To all whom it may concern:

Be it known that I, ERNEST G. MCLEOD, a citizen of the United States, residing in Brockton, in the county of Plymouth and 5 State of Massachusetts, have invented a new and useful Improvement in Fountain-Pens, of which the following is a specification.

This invention relates to improvements in fountain pens and more particularly to 10 that type of fountain pen commonly known as the "Waterman".

Objects of the invention are to prevent leaking or sweating of ink from the pen and to facilitate the starting of the flow of 15 ink when the pen is used.

The invention furthermore consists in the improvements in the parts and devices and in the novel combinations of the parts and devices herein shown, described or claimed.

20 In fountain pens as hitherto constructed and especially those of the Waterman type and others employing a threaded pen section, I have found that much annoyance and inconvenience is caused, due to ink leaking or sweating out of the end of the pen and spreading over that portion ordinarily grasped by the user while writing, thus causing ink stains on the user's fingers. The sweating or leaking generally takes 25 place while the pen is being carried in the pocket and especially when the supply of ink within the reservoir or barrel is running low. This action, I have discovered, is due to the expansion of the air within the bar- 30 rel caused by heat from the person's body which forces out, through the feed tube or passage in the feeder within the pen section, a certain amount of ink left therein after the pen has been used, which ink does 35 not properly drain back into the barrel or reservoir, as it should, when the pen is placed upright in the pocket. In most fountain pens, of the type above referred to, the small feed passage that conducts the ink to 40 the pen point has its inner end removed from the wall of the barrel or reservoir and on account of the small cross-sectional area of this passageway, the ink forms a film or liquid seal over the end thereof when the 45 pen is placed in an upright position, due to capillary attraction, and it is this seal or film which prevents that portion of the ink remaining in the passage from draining back into the barrel or reservoir. As the air

pressure within the pen increases and thus forces the ink out at the end of the pen.

By experiment I have demonstrated that if a direct path for the ink is provided from the inner end of the passage to the inner 60 wall of the barrel or reservoir, that all ink will be completely drained from this passage back into the barrel and that thereafter any expansion of air within the pen, can be accommodated by escape through the 65 ink feed passageway and that no sweating or leaking of the ink occurs. Furthermore by providing this direct path for the ink between the feed passageway, the ink starts to flow readily when the pen is held in an inverted 70 position thus obviating the necessity for shaking or jarring of the pen as is now often necessary with the present construction of fountain pens.

The objects of my invention are attained 75 by the construction shown in the drawing forming a part of this specification, wherein—

Figure 1 is a longitudinal sectional view of a fountain pen embodying my improvements. Fig. 2 is a longitudinal sectional view, upon an enlarged scale, taken through the pen section and Fig. 3 is a transverse sectional view taken substantially on the line 3—3 of Fig. 2.

80 In the drawing 10 denotes the main body portion of the fountain pen adapted to serve as the reservoir or barrel for the supply of ink and which, as shown, is provided at one end with an interiorly threaded portion 11 with which cooperates a correspondingly exteriorly threaded tubular portion 12 of the pen section 13, said pen section and barrel 12 being tapered as at 14 to facilitate insertion into the usual form of cap 15. The 90 pen section 13, as is usual in the type of fountain pen heretofore referred to, is provided with a feeder 16 which terminates at its inner end generally approximately a sixteenth of an inch within the inner edge 17 of the threaded tubular portion 12 of the pen section. This feeder 16 is also provided with a tubular duct or feed passage 18 through which the ink is adapted to be conducted to the pen 19. In order to form a 95 pathway for the ink in draining from the feeder when the fountain pen is placed in an upright position and to prevent a film or liquid seal from being formed over the inner end of the feed passageway 18, I cut 100

105

110

55 within the barrel or reservoir expands, the

2
a notch 20 in the threaded tubular portion 12 of the pen section, which notch, as will be apparent from an inspection of the drawing, forms a path for the ink from the feed passageway to the inner wall 21 of the barrel or reservoir. The notch 20 communicates with or intersects the feed passageway 18 and also extends through the tubular portion 12 to the periphery thereof and 10 the notch thus formed will have sharp edges 22 which will assist in draining the ink from the passageway and prevent a seal being formed over the end thereof.

When it is desired to use the pen, the ink 15 will readily flow to the pen point since there will be no seal or film to be broken at the inner end of the ink feed tube or passageway 18.

Although I have shown and described 20 only one form of my improvements which I consider preferable, yet it will be obvious to those skilled in the art that changes and variations may be made in the details thereof without departing from the spirit of the 25 invention and all such changes and variations are contemplated as fall within the scope of the claims appended hereto.

I claim:—

1. In a fountain pen, in combination: an 30 ink barrel having a screw threaded portion;

a pen section coöperating with said barrel and having a pen secured thereto, said pen section being provided with a feeder having an ink feed passage extending to the inner end thereof and terminating within the 35 periphery of the pen section, said pen section having a notch at its extreme inner end cut through the periphery thereof and intersecting said feed passage to thereby provide a direct path for the ink from the feed passage to the inner wall of the barrel and vice versa, substantially as specified. 40

2. In a fountain pen, in combination: an ink barrel; a pen section provided with an ink feed passage extending to the inner end 45 thereof, said pen section being provided with means for causing the ink to drain from the feed passage directly to the inner wall of the barrel, said means comprising a cut-out portion in the pen section extending from the feed passage clear to the inner wall of the barrel and forming a path for the ink from the feed passage directly to the inner wall of the barrel, substantially as specified. 50
